UNITED STATES PATENT OFFICE.

THOMAS J. STEARNS, OF BOSTON, MASSACHUSETTS.

DESIGN FOR CARPET.

SPECIFICATION forming part of Design No. 11,803, dated June 1, 1880.

Application filed March 15, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design consists in a series of scrolls arranged in intersecting convolutions, blossoms A, of various forms, at the ends of nearly all of the convolutions, and floral or bell-shaped ornaments B, each having pendent balls, as shown.

I am aware of the design patented to J. T. Webster, No. 7,695, August 18, 1874, showing

scrolls arranged in intersecting convolutions, but devoid of the blossoms A and ornaments B, so prominent in my design.

I claim—

The design for a carpet, consisting of the scrolls ornamented by the terminal blossoms A and the bell-shaped figures B, having pendent balls, substantially as shown.

In testimony whereof I have signed my name to this specification, in the presence of two subscribing witnesses, this 12th day of March, 1880.

THOMAS J. STEARNS.
